UNITED STATES PATENT OFFICE.

DANIEL F. LEPLEY, OF CONNELLSVILLE, PENNSYLVANIA.

LEVELER FOR CHARGES OF COKE-OVENS.

1,129,352.

Specification of Letters Patent.

Patented Feb. 23, 1915.

Application filed August 31, 1910. Serial No. 579,856.

To all whom it may concern:

Be it known that I, DANIEL F. LEPLEY, a citizen of the United States, residing at Connellsburg, in the county of Fayette and State 5 of Pennsylvania, have invented a new and useful Leveler for Charges of Coke-Ovens, of which the following is a specification.

This invention has reference to improvements in means for leveling a fuel charge in 10 an oven, preparatory to firing the same, and the invention aims to produce a device which may be adapted readily to different ovens, regardless of variations in the height of the same, the device being adapted to bring 15 the pile of material within the oven to a substantially level surface by the movement of the leveling apparatus into and out of the oven.

The invention will be understood best 20 from a consideration of the following detailed description taken in connection with the accompanying drawings.

In the drawings:—Figure 1 is a side elevation of the coke leveler; Fig. 2 is a plan view of the same; Fig. 3 is a front elevation, the leveling head being omitted; Fig. 4 is a detail elevation (on a larger scale than the other figures) of the means for elevating and lowering the leveler-carrying-portion of 25 the structure; Fig. 5 is an elevation of the structure of Fig. 4 as seen from a point at right angles to the view point of Fig. 4, certain parts being in section to show the bearings; Fig. 6 is a structural diagram 30 showing the means for operating the leveler; Figs. 7, 8 and 9 are diagrammatic views showing the arrangement of the cables which actuate the plunger or ram; and Fig. 10 is a top plan, diagrammatic in nature, the 35 view depicting the means whereby a vertical adjustment and a tilting of the ram are effected.

Coke ovens of the type to which this invention is particularly adapted, are built in 40 long rows with a yard extended to one or both ends of the row, and along the face of the ovens in the yard, there is laid a track.

In the drawings, the ovens are indicated at 1 and the track is indicated at 2. Adapted 45 to traverse the track 2 is a truck 3 which need not be particularly described, since the specific structure of the truck forms no part of the present invention.

Mounted at an appropriate point on the 50 truck 3, as shown in Figs. 1, 2 and 3, is an

electric motor 4, on the armature shaft of which is a gear pinion 5 meshing into a gear wheel 6 secured to a shaft 7 which is suitably supported for rotation on the truck 3. Journalized on the shaft 7 as shown in Figs. 4 and 5 is a sprocket wheel 11, connected by means of a sprocket chain 14 with a sprocket wheel 13 which is secured to one of the axles 12 of the truck 3. Mounted on the shaft 7 is a clutch 9 whereby the sprocket wheel 11 may be coupled with the shaft 7. Thus, when the motor 4 is in operation, the truck 3 may be moved to and fro along the track 2 through the medium of a gear train comprising the pinion 5, the gear wheel 6, the shaft 7, the clutch 9, the sprocket wheel 11, the sprocket chain 14, the sprocket wheel 13 and the axle 12 of the truck.

Referring particularly to Figs. 5 and 10 it will be observed that a pair of sprocket 75 wheels 10 and 10^a are journalized on the shaft 7, and either one of the sprocket wheels 10 and 10^a may be coupled up with the shaft 7 through the medium of a clutch 8. Another pair of sprocket wheels 10^b and 10^c are journalized on the shaft 7, and these sprocket 80 wheels respectively, may be coupled up with the shaft 7 through the medium of a clutch 8^a.

Supported by the side portions of the 85 frame of the truck 3 are shafts 22 and 22^a, reference being had particularly to Figs. 4, 5 and 10. Journalized on one end of the shaft 22 is a sleeve 102 carrying a sprocket wheel 24, connected by means of a sprocket chain 90 25^b with the sprocket wheel 10^a on the shaft 7. The sleeve 102 is provided at its outer end with a beveled gear 21. Journalized on the shaft 22^a at the same side of the machine as the sleeve 102, is a sleeve 105 provided with 95 a sprocket wheel 24^b connected by means of a sprocket chain 25 with the sprocket wheel 10 of the shaft 7. Secured to the outer end of the sleeve 105 is a beveled gear 21^a. At the opposite side of the machine, a sleeve 101 is journalized on the shaft 22, the sleeve 101 being provided with a sprocket wheel 24^a about which is trained a sprocket chain 25^c, the sprocket chain 25^c being connected with the sprocket wheel 10^b upon the shaft 7. 100 The sleeve 101 carries at its outer end a beveled gear 21. Journalized upon the shaft 22^a at the same side of the machine as the sleeve 101 is a sleeve 103 to which is secured 105 a sprocket wheel 24^c connected by means of 110

a sprocket chain 25^a with the sprocket wheel 10^c on the shaft 7. At its outer end, the sleeve 103 carries a beveled pinion 21^a.

Referring to Fig. 5 and comparing the 5 same with Fig. 4, it will be observed that the frame of the truck 3 is provided upon opposite sides with bearings 15, receiving vertical rods 16, terminated at their upper ends in eyes 18, the lower parts of the rods 16 being 10 threaded as indicated at 17, to engage with beveled gear wheels 19 and 19^a. There is a pair of rods 16 at each side of the machine. One rod 16 is threaded into the beveled gear wheel 19 and the other rod is threaded into 15 the beveled gear wheel 19^a. Upward movement of the gear wheels 19 and 19^a is prevented by the bearing 15, and downward movement of the gear wheels is prevented by a plate 20, constituting a part of the 20 frame of the truck. The beveled gear wheels 19 and 19^a at each side of the truck are connected operatively by means of united beveled gears 23, suitably supported for rotation along the sides of the frame of the 25 truck.

Suppose that the sprocket wheel 10^a is coupled to the shaft 7 by means of the clutch 8, the sprocket wheel 10^b being coupled to the shaft 7 by means of the clutch 30 8^a. When rotatory movement is imparted to the shaft 7 from the motor 4, motion will be transmitted from the sprocket wheel 10^a to the sprocket chain 25^b, and thence into the sleeve 102 by way of the sprocket wheel 35 24. The beveled pinion 21 at one side of the machine will actuate the beveled pinion 19 and the beveled pinion through the medium of the connected beveled pinions 23 will actuate the beveled gear wheel 19^a upon 40 the same side of the machine. In this manner, the rods 16 at one side of the machine will be lifted simultaneously, presupposing that the shaft 7 is rotated in the proper direction.

From the sprocket wheel 10^b motion will 45 be transmitted through the sprocket chain 25^c to the sprocket wheel 24^c, and thence into the sleeve 101, the sleeve 101 through the medium of the other beveled gear 21, the beveled gear 19, the beveled pinions 23 and 50 the corresponding beveled gear 19^a effecting an elevation of the rods 16 at the side of the machine in question. Suppose, however, that through the medium of the clutch 8, the sprocket wheel 10 has been coupled to 55 the shaft 7 and suppose that through the medium of the clutch 8^a, the sprocket wheel 10^c has been coupled up to the shaft 7. Then, motion will be transmitted from the sprocket wheel 10 to the chain 25, through 60 the sprocket wheel 24^b, to the sprocket sleeve 105 and to the beveled gear 21^a and attendant parts, the rods 16 being lowered, presupposing that the shaft 7 has been rotated as above described. From the sprocket 65 wheel 10^c, motion will be transmitted

through the sprocket chain 25^a to the sprocket wheel 24^c, and thence by way of the sleeve 103 to the other beveled pinion 21^a and attendant parts. Thus the rods 16 upon corresponding sides of the machine will be 70 lowered.

By the operation above described, all of the rods 16 have been raised and lowered with their upper, eye carrying portions 18 in a single horizontal plane. It is obvious, 75 however, that the sprocket wheels 10^b and 10^a may be coupled simultaneously to the shaft 7. Likewise, the sprocket wheel 10^c and the sprocket wheel 10 may be coupled simultaneously to the shaft 7, thus effecting 80 independent movement between the pairs of rods 16 at opposite sides of the machine, so that the eye carrying portions 18 of the rods 16 may be disposed at different elevations. Likewise, by the proper manipulation of the 85 clutch 8, the sprocket wheels 10^c and 10^b may be coupled individually to the shaft 7 to effect a proper vertical adjustment of the pairs of rods 16 at the respective sides of the machine.

When the clutch 8 is disengaged from the 90 pinions 10 and 10^a and when the clutch 8^a is disengaged from the sprocket wheels 10^b and 10^c, the shaft 7 may be driven from the motor 4 to impart movement to the axle 12, 95 in the manner hereinbefore set forth.

Erected on the truck 3 are upright spaced guides 26 adapted to direct the movement of a frame F made up of side plates 27. Secured to the side plates 27 of the frame F are 100 blocks 28, receiving pins or bars 29. The bars 29 pass through the eyes 18 of the rods 16 at opposite sides of the frame, and from what has been said hereinbefore it will be obvious that a vertical movement imparted 105 to the rods 16 will effect a vertical adjustment of the frame F.

Noting particularly Figs. 1 and 2 it will be seen that an electric motor 30 is mounted on top of the frame F. The motor 30 is 110 geared as indicated at 30^a to a shaft 31 which is supported for rotation on top of the frame F. Secured to the shaft 31 is a beveled gear 32 meshing with two opposite beveled gears 33—34 fixed respectively, to 115 shafts 35 and 36. Fixed to the outer ends of the shafts 35 and 36 are gear wheels 37 which mesh with gear wheels 38. The gear wheels 38 are journaled for rotation on a shaft 40 which is journaled on the frame F, 120 clutches 39 being provided, for the purpose of coupling up the gear wheels 38 with the shaft 40. A drum 41 is secured to the shaft 40, and secured to the shaft 40 upon opposite sides of the drum 44 are outer drums 42. By 125 reason of the gear connection between the motor 30 and the gear wheels 38, these wheels rotate in opposite directions. By manipulating the clutches 39 of the shaft 40, the shaft, therefore, may be driven in 130

one direction or in an opposite direction, at the will of the operator. In order that the operator may have control of the machine as a whole, the truck 3 supports a cab C shown 5 most clearly in Fig. 3, and in the cab C are located suitable controlling means for the motors and the clutches, but since such means may be of any desired form, a specific description thereof need not be entered into 10 in this specification.

Traversing the casing F at the front and at other appropriate points are spaced pairs of rollers 44 receiving between them a rectangular tubular member 45 simply indicated in Fig. 6 but which may be made in any appropriate manner for the purposes of the present invention. This box forms one section of the leveler ram and the other section is in telescoping relation to the first 15 section and as shown comprises a pipe 46 supported at the rear end by a truck formed of short axles 47 carrying wheels or rollers 48 arranged to travel in the first section 45 of the ram structure, as shown in Fig. 2. At 20 the outer end of the second section of the ram there is a head 49 which may be variously shaped in accordance with the desires of the designer. In the particular structure shown in the drawings there is a cross angle member 50 fast to the pipe 46 a 25 short distance from the outer end thereof and extending from near the ends of the cross member 50 to the outer end of the pipe is another angle member 51 of general taper 30 form while the ends of the cross member 50 are protected by shoes 52 which will engage the side walls of the oven and so guide the head 49 when in the oven.

At the rear of the ram member 45 there 35 are brackets 53 or other suitable fastening devices as shown in Fig. 6. Made fast to the drum 41 are the ends of two strands 54, preferably steel ropes, and these ropes are wound an appropriate number of times 40 around the drum and are then carried about direction changing idler rollers 55 and are continued from thence to the brackets 53 to which the ends of the ropes 54 are made fast. Secured each at one end to respective ones 45 of the brackets 53 are other ropes 54' carried about direction changing idler rollers 55 to the drum 41 about which the ropes 54' are wound an appropriate number of times 50 alongside the ropes 54 in non-interfering relation thereto, and the ends of the ropes are secured to the drum, it being customary to provide the drum 41 with grooves for the purpose after the usual practice. The ropes 54' are wound on the drum in the opposite 55 direction to the ropes 54 so that one set of ropes unwinds as the other winds upon the drum.

The ram member 46 at the rear end carries a fastening device 58 to which are fastened the like ends of two strands 59, 60

which like the strands 54 and 54' may be made of steel rope. One rope, say the rope 59 extends to and is wound about one drum 42 while the other rope 60 extends to and is wound about the other drum 42. See 70 Fig. 7. There is also provided another strand 61 in the form of a steel rope, one end being made fast to a fixed portion of the structure, say the rear end of the frame F. This rope 61 extends about a direction 75 changing idler roller 62 at the front of the ram section 45, thence to the rear end of the ram section 46 where it passes about a direction changing idler roller 63 carried by said ram section 46 thence about another 80 idler roller 64 corresponding to the roller 62 and finally back again through the rear end of the ram section 45 to a fixed point of the frame F.

Let it be assumed that the ram is in the 85 retracted or telescoped position, then if power be applied to the drum 41 to rotate it in the proper direction the ropes 54' will cause a movement of the ram section 45 outward from the casing F in which it is normally housed. Because of the fixture of the rear ends of the rope 61 to the casing or frame F these ends of the rope 61 do not participate in the movement of the ram but the rope 61 reacts on the roller 63 to carry 90 the ram section 46 outward with the ram section 45, but because the rope 61 passes about the rollers 62 and 64 the ram section 46 will have imparted thereto a speed double 95 that of the ram section 45. When the parts 100 have been projected to the greatest extent, then the drum 41 may be reversed and the strands 54 passing around the rollers 55 will then act to draw the ram section 45 into the frame 27.

During the first operation, that of projecting the leveler ram, the drum 42 simply turned idly permitting the paying out of the ropes 59 and 60. Now however power is applied to these drums 42 to wind the ropes 110 59 and 60 thereon, thus aiding in withdrawing the ram section 46 to telescoping relation to the ram section 45, this being advisable because of the resistance offered to the rear end of the leveler head 49 by the material 115 being acted upon.

The mechanism above described and shown in diagram in Fig. 7 serves to take up the slack in the cable 61 and to telescope the ram section 46 into the ram section 45.

When the ram is first introduced into the coke oven the fuel charge is in the form of a heap highest at the center and the head 49 engages such material and forces it toward the other end of the oven and then on the return movement the rear edge of the head 49 also engages the material and draws it toward the first end of the oven. This operation may be continued as long as necessary to level all the material in the oven 130

when the ram may ultimately be withdrawn from the oven so that the section 45 is telescoped within the casing or frame F and the section 46 is telescoped within the section 45. Any change in elevation necessary for the frame or casing F to bring the leveling head 49 into proper relation to the material to be leveled may be accomplished by a proper adjustment of the screw rods 16 in the manner already described. Because of the independent operation of either set of rods 16 the leveler ram may be caused to move in an inclined path rising or falling as desired with reference to the floor of the oven. The telescoping leveling head actuating devices greatly reduce the extent of the leveling machine from the breast of the oven bank. It will be observed that since the relative movements of the ram sections 45 and 46 are as one to two, the drums 41 and 42 have the same relation as to their size.

What is claimed is:

1. In a leveler for fuel charges of coke ovens, a leveling ram; a support therefor; a truck; movable members upheld by the truck and connected to the support at spaced points; mechanism for operating the movable members separately and together, to move the support vertically and to tilt the support; and means for actuating the ram.
2. In a leveler for the fuel charges of coke ovens, a leveling head, a two part telescoping carrier therefor with the inner member carrying the leveling head at one end, supporting wheels for the inner member at the other end, an actuating drum and a flexible strand connection therefrom to the outer member of the carrier for causing the movement of the latter in both directions, other driving drums and flexible strand connections to the rear end of the inner member of the carrier, and a flexible strand connected at its ends to a fixed part of the structure and extending from thence to the front end of the outer member of the carrier, thence to the inner end of the inner member of the carrier, and direction diverting rollers at the outer end of the outer member of the carrier, and at the inner end of the inner member of the carrier for the last named strand.
3. In a leveler for fuel charges of coke ovens, a leveling ram; a support therefor; a truck; means for advancing and retracting the ram; movable members upheld by the truck and connected to the support at

points spaced transversely of the direction of advance and retraction of the ram; and mechanism for operating the movable members separately and together, to move the support vertically and to tilt the support transversely of the direction of advance and retraction of the ram.

4. In a leveler for fuel charges of coke ovens, a leveling ram; a support therefor; a truck; means for advancing and retracting the ram; movable members upheld by the truck and connected to the support at points spaced both longitudinally and transversely of the direction of advance and retraction of the ram; and mechanism for operating the movable members separately and together, to move the support vertically and to tilt the support longitudinally and transversely of the direction of advance and retraction of the ram.

5. In a leveler for fuel charges of coke ovens, a leveling ram; a support therefor; means for actuating the ram with respect to the support; a truck; movable members connected to the support at spaced points; rotatable elements on the truck and operatively connected with the movable members to actuate the same separately and together, thereby to move the support vertically and to tilt the support; a motor working in a single direction; and selectively operable clutches forming operative connections between the rotatable elements and the motor.

6. In a leveler for fuel charges of coke ovens, a leveling ram; a support therefor; means for actuating the ram with respect to the support; a truck; movable members connected to the support at spaced points; rotatable elements on the truck and operatively connected with the movable members to actuate the same separately and together, thereby to move the support vertically and to tilt the support; a motor working in a single direction; selectively operable clutches forming operative connections between the rotatable elements and the motor; and manually operable means for actuating the clutches.

In testimony that I claim the foregoing as my own, I have hereto affixed my signature in the presence of two witnesses.

DANIEL F. LEPLEY.
